(57) **CLAIM**

The ornamental design for a security tag as shown and described.

DESCRIPTION

FIG. 1 is a perspective view of the security tag in accordance with my new design, with the security tag in a first configuration, in which a button is pressed in;

FIG. 2 is another perspective view of the security tag depicted in FIG. 1;

FIG. 3 is another perspective view of the security tag depicted in FIG. 1;

FIG. 4 is a left side view of the security tag depicted in FIG. 1;

FIG. 5 is a right side view of the security tag depicted in FIG. 1;

FIG. 6 is a front view of the security tag depicted in FIG. 1;

FIG. 7 is a rear view of the security tag depicted in FIG. 1;

FIG. 8 is a top view of the security tag depicted in FIG. 1;

FIG. 9 is a bottom view of the security tag depicted in FIG. 1;

FIG. 10 is a perspective view of the security tag in accordance with my new design, with the security tag in a second configuration, in which a button is extending from a top portion of the security tag;

FIG. 11 is another perspective view of the security tag depicted in FIG. 10;

FIG. 12 is another perspective view of the security tag depicted in FIG. 10;

FIG. 13 is a left side view of the security tag depicted in FIG. 10;

FIG. 14 is a right side view of the security tag depicted in FIG. 10;

FIG. 15 is a front view of the security tag depicted in FIG. 10;

FIG. 16 is a rear view of the security tag depicted in FIG. 10;

FIG. 17 is a top view of the security tag depicted in FIG. 10;

and,

FIG. 18 is a bottom view of the security tag depicted in FIG. 10.
